UNITED STATES PATENT OFFICE.

WILLIAM SCHLIE, OF CHICAGO, ILLINOIS.

TRAP-NEST.

SPECIFICATION forming part of Letters Patent No. 700,245, dated May 20, 1902.

Application filed January 20, 1902. Serial No. 90,396. (No model.)

To all whom it may concern:

Be it known that I, WILLIAM SCHLIE, a citizen of the United States, and a resident of Chicago, county of Cook, and State of Illinois, 5 have invented certain new and useful Improvements in Trap-Nests, of which the following is a specification and which are illustrated in the accompanying drawings, forming a part thereof.

10 This invention relates to a trap-nest which is particularly adapted for use in connection with poultry-breeding. In this art in order to secure the best results it is necessary to use eggs from good layers and those that have 15 hard shells and the right color, and it is of course in this connection required to keep a record of each fowl, so as to know her laying ability and the quality of the eggs secured from her.

20 By the use of the invention herein described the desired information may readily be secured, as it will be known from what hen any egg is procured, thereby enabling an accurate and detailed record to be kept.

25 Generally stated, the invention consists of a movable nest provided with means whereby the door of the entrance to the nest-compartment is automatically closed when a hen goes on the nest and means for indicating 30 through the medium of an indicator or alarm the presence of an egg in the nest, the arrangement being such that until the egg is removed the door to the nest is held in its closed position, thereby preventing the hen 35 from leaving the compartment in which the nest is located. When, therefore, the attendant whose attention has been attracted by the alarm goes to take out the egg, he will see what hen has layed the same and may acquire 40 the necessary information for his record-book.

The invention consists in the novel construction and combination of parts, as will be hereinafter fully set forth, and particularly designated in the appended claims, and is illustrated in the accompanying drawings, in which—

Figure 1 is a plan view of the nest, the top wall of the compartment being removed. Fig. 2 is a section on the line 2 2 of Fig. 3, illustrating in plan a portion of the lever which is tripped by the movable nest to close the door of the entrance to the nest-chamber. Fig. 3

is a vertical longitudinal section of the nest and its compartment, a portion of the top being broken away and some of the parts being 55 shown in full lines. Figs. 4 and 5 relate to details.

The nest is located in a chamber or compartment 9, closed by the walls 10, the front only being open and provided with a vertically-sliding door or gate 11, playing in grooves 12 in the opposite walls of the nest-chamber. Located in the rear of the compartment 9 is the nest proper, which consists of a vertically-moving frame 13, guided in its movement by the rear and side walls of the compartment 9 and having a downwardly-tapering bottom 14.

Pivoted to a support 15, at the bottom of the compartment 9 and extending longitudinally thereof, is a lever 16, whose outer end is connected by means of a link 17 to the sliding door 11. The inner end of the lever 16 is designed to be tripped by the nest in its movement, the relative weights of the door and nest 75 being such that when a hen goes on the nest her weight in addition to that of the nest will be sufficient to lift the door and close the entrance to the compartment 9. With this in view the inner end of the lever 16 is bifurcated or provided with a pair of arms 18 18^a, which extend to the depending side walls 19 of the nest-frame 13 and are provided with notches 20 to receive pins 21 21^a, fixed in the said side walls.

85 The bottom 14 of the nest is provided with a central opening 22, below which is supported a cup-shaped pocket or receptacle 23 by means of a depending arm or loop 24, fixed thereto, and a lever 25, jointed to the arm and pivoted on a transverse bar 26, carried by the depending side walls 19. An adjustable counterbalance-weight 27 is carried by the lever 25 and is set so as to hold the pocket 23 when empty up against the nest-bottom 14, but 90 which will be overcome by the weight of an egg and permit the pocket or receptacle to move downwardly away from the aperture of the bottom 14. The parts 14 and 23 of the nest are preferably covered with some suitable material, such as cotton-batting or wool, forming a soft nest-bottom for the poultry.

95 The outer side of the rear wall of the nest compartment is provided with an indicating

device, which may consist, as shown, of a hinged plate 28, located over a slot 29, in which is pivoted at 30 a lever 31, the lower end of which has a finger or, as shown, a pair 5 of fingers 32, projecting into the chamber 9 below the movable nest and below and at opposite sides of a detent 33, secured to the rear wall thereof.

Pivoted at 34 over the detent 33 and to the 10 frame 13 of the nest is a loop 35, having an arm or arms 36, jointed to the loop 24, depending from the egg-pocket 23.

An approach 37 within the nest-compartment leads from the entrance closed by the 15 door 11 to the nest. When a fowl goes on the nest, the frame 13 is lowered by her weight, and through the medium of the lever 16 the door 11 is lifted and the entrance closed, the dropping of the nest also carrying the bottom 20 of the loop 35 below the detent 33 and the fingers 32 of the lever 31, although it still remains in front of the same and away from the rear wall of the compartment.

When now the fowl deposits an egg, the 25 weight thereof overcomes the weight 27 and the pocket 23 drops, moving through the medium of the arms 36, the arm or loop 35 toward the rear wall of the nest-compartment and bringing the bottom thereof under the 30 fingers 32 of the lever 31. As the hen leaves the nest and walks onto the platform 37 the frame 13 rises, carrying with it, of course, the loop 35, which soon engages the fingers of the lever 31 and turns the latter on its pivot, 35 thereby throwing the hinged indicator outwardly, the upward movement of the nest continuing until the detent 33 is engaged by the bottom of the loop 35, although it is not in any event sufficient to open the door, so as 40 to permit the hen to depart. The indicator being in a position to be observed by the attendant, he is enabled to see through a door-closed opening located in the rear wall of the compartment and provided for the purpose 45 what hen has deposited the egg and to note her number. He then removes the egg from the nest. This permits the weight 27 to lift the pocket 23 to its normal position, and the pocket in rising disengages the loop 50 35 from the detent 33, permitting the weight of the gate 11 to overcome the weight of the nest and fall, opening the entrance and allowing the hen to leave, the indicator also dropping back to its original position.

55 The nests are usually arranged in banks of six or more compartments, and there are generally provided two or more banks in each fowl-pen and so located that the indicator of each nest is toward a common passage-way 60 between the pens, so that the attendant may readily see from an inspection of the indicators in what nests eggs have been laid; but this requires where there are a large number of pens the constant presence of an attendant. In order to avoid this, I preferably 65 employ an electric alarm, which may be arranged as shown in Fig. 3. The battery and

bell and an annunciator common to all the pens may also be provided, if desired, to indicate in what bank of nests the alarm is 70 being rung and are preferably located in the attendant's room or office. In the circuit a connection leads from the battery by the wire 75 38 to a plate 39, secured to the rear wall of the compartment 9 and in such position as to be engaged by the arm or loop 35 when the latter actuates the indicator 28 up the loop 35, thence by wire 40 to the pin 21^a, and out the lever 18^a through the wire 41 and the alarm to the battery. 80

It will be understood from the foregoing that when the arm or loop 35 is lifted by the partial upward movement of the nest the lower end thereof will come in contact with the plate 39, thereby closing the circuit and ringing the alarm, and that the circuit will again be opened when the egg is removed, the contact of the loop with the plate 39 then being broken. 85

I claim as my invention— 90

1. In a device of the character described, in combination, a nest-compartment, a movable nest therein, a door closing the entrance to the nest-compartment, connection between the nest and the door whereby movement of one will actuate the other, and means controlled by the egg deposited in the nest for holding the nest when depressed from rising. 95

2. In a device of the character described, in combination, a nest-compartment, a vertically-movable nest therein, a door, connection between the door and the nest, a movable pocket in the bottom of the nest, means actuated by the pocket for holding the nest when depressed from rising, an indicator, and means also actuated by the pocket for operating the indicator. 100

3. In a device of the character described, in combination, a nest-compartment, a vertically-movable nest therein, a door closing the entrance to the compartment, connection between the door and the nest whereby movement of one will actuate the other, a movable pocket in the bottom of the nest, a detent, and an arm actuated by the movable pocket 115 for engaging the detent to hold the nest when depressed from rising. 110

4. In a device of the character described, in combination, a nest-compartment, a vertically-movable nest therein, a door closing the entrance to the compartment, a lever connection between the nest and the door whereby movement of one will actuate the other, a movable pocket in the bottom of the nest, a counterbalance-lever to which the pocket is 125 pivoted, a pivoted arm, connection between the arm and the pocket, and a detent engaged by the arm to hold the nest when depressed from rising. 120

5. In a device of the character described, in combination, a nest-compartment, a vertically-movable nest therein, a door adapted to close the entrance to the compartment, a lever connected at one end to the door and hav-

- ing its opposite end extending in the path of the nest, a movable pocket in the bottom of the nest, a pivoted lever connected to the pocket, a counterbalance-weight on the lever, 5 a pivoted loop actuated by the pocket, an indicator hinged to the wall of the nest-compartment, a lever actuated by the loop for operating the indicator, and a detent engaged by the loop for holding the nest when de- 10 pressed from rising.
6. In a device of the character described, in combination, a nest-compartment, a vertically-movable nest therein, a door closing the entrance to the nest-compartment, connection 15 between the nest and the door whereby movement of one will actuate the other, means for holding the nest when depressed from rising, an alarm, an electric circuit therefor, and means controlled by the movable nest for 20 closing the circuit.
7. In a device of the character described, in combination, a nest-compartment, a vertically-movable nest therein, a door closing the entrance to the nest-compartment, connection 25 between the nest and the door whereby movement of one will actuate the other, means for holding the nest when depressed from rising, a battery, a contact-plate, connection between the battery and the plate, connection 30 between the battery and the means for holding the nest whereby the circuit is closed when the nest is held in its lowered position, and an alarm in the connection.
8. In a device of the character described, in combination, a nest-compartment, a vertically-movable nest therein, a door closing the entrance to the nest-compartment, connection 35 between the nest and the door whereby movement of one will actuate the other, a movable pocket in the bottom of the nest, means actuated by the movable pocket for holding the nest when depressed from rising, an alarm, an electric circuit therefor, means controlled by 40 the movable pocket for closing the circuit, and an indicator controlled by the means actuated by the movable pocket.
9. In a device of the character described, in combination, a nest-compartment, a vertically-movable nest therein, a door closing the 45 entrance to the nest-compartment, connection between the nest and the door whereby movement of one will actuate the other, a movable pocket in the bottom of the nest, a counterbalance-lever to which the pocket is pivoted, 50 a pivoted arm, connection between the arm and the pocket, an indicator hinged to the wall of the compartment, a lever actuated by the pivoted arm for operating the indicator, a de- 55 tent engaged by the arm for holding the nest when depressed from rising, a battery, a plate located at the side of the detent, connection 60 between the battery and the plate, connection between the battery and the pivoted arm, and an alarm in one of said connections, the parts being so disposed that when the arm engages 65 the detent the circuit will be closed and the alarm rung.
10. In a trap-nest, in combination, a nest-compartment, a movable nest therein, a door closing the entrance to the nest-compartment, connection 70 between the nest and the door whereby movement of one will actuate the other, a movable pocket in the nest, and means controlled by the pocket for holding the nest when moved from returning to its original 75 position.
11. In a trap-nest, in combination, a nest-compartment, a movable nest therein, a door for the nest-compartment, means actuated by the nest for closing the door, and means controlled by the egg deposited in the nest for holding the nest when moved from returning to its original position. 80
12. In a trap-nest, in combination, a nest-compartment, a vertically-movable nest therein, a door for the nest-compartment, means actuated by the nest for closing the door, means actuated by the egg deposited in the nest for holding the nest when depressed from rising, an indicator, and means controlled by 90 the movable nest for operating the indicator. 85
13. In a device of the character described, in combination, a vertically-movable nest having an independently-movable egg-pocket, yielding supports for each member, an electric signal, a switch in the circuit thereof, and means actuated by the independent movement of the said members for closing the switch. 95
14. In a trap-nest, in combination, a nest-compartment, a movable nest therein, a door for the nest-compartment, means actuated by the nest for closing the door, an indicator, an alarm, and means controlled by the movable nest for operating the indicator and for closing the circuit to actuate the alarm. 100
15. In a device of the character described, in combination, a nest-compartment, a nest therein and having a movable bottom, an alarm, an electric circuit, and a lever controlled by the movable bottom and for closing the circuit to actuate the alarm. 105
